UNITED STATES PATENT OFFICE.

MARY KAVANAGH, OF NEW YORK, N. Y., ASSIGNOR TO THE BUTTERICK PUBLISHING COMPANY, (LIMITED), OF SAME PLACE.

DESIGN FOR A LADY'S COSTUME.

SPECIFICATION forming part of Design No. 15,091 dated June 24, 1884.

Application filed May 12, 1884. Term of patent 3 years.

To all whom it may concern:

Be it known that I, MARY KAVANAGH, of the city, county, and State of New York, have invented and produced a new and original Design for a Pattern of a Lady's Costume, (numbered 9,238;) and I do hereby declare that the engraved prints accompanying this specification convey to any one accustomed to using paper patterns a clear understanding of how to a garment made up by the pattern will appear.

The design shows a round walking-skirt and a basque. The skirt displays a front drapery, exhibiting draping plaits in its back edges and falling in a deep point at the left side, and a 15 side-plaited back drapery falling nearly to the bottom of the skirt. The basque exhibits

closely-fitted fronts that describe a point at the lower end of the closing and a high arch at the sides, a closely-fitted back falling deep and square, and exhibiting under-folded plaits 20 at the ends of its middle three seams and at its front edges, a standing collar, and coat-sleeves.

What I claim as my invention, and desire to secure by Letters Patent, is—

The design for a lady's costume, as shown in 25 the engraved prints accompanying this specification.

MARY KAVANAGH.
